UNITED STATES PATENT OFFICE.

ALTON W. INGALLS, OF REDLANDS, CALIFORNIA.

DIRECTION-INDICATOR FOR MOTOR-VEHICLES.

1,323,866.

Specification of Letters Patent.

Patented Dec. 2, 1919.

Application filed July 1, 1918. Serial No. 242,837.

To all whom it may concern:

Be it known that I, ALTON W. INGALLS, a citizen of the United States, residing at Redlands, in the county of San Bernardino and State of California, have invented new and useful Improvements in Direction-Indicators for Motor-Vehicles, of which the following is a specification.

My invention relates to direction indicators and consists in the novel features herein shown, described and claimed.

Figure 1 is a diagrammatic view showing a direction indicator embodying the principles of my invention in use upon the forward and rear ends of an automobile and controlled from the steering post.

Fig. 2 is an enlarged perspective of the indicator mechanism at the forward end of the automobile in Fig. 1.

Fig. 3 is a vertical central sectional detail on the line 3—3 of Fig. 2.

Fig. 4 is a projected plan of the sheet forming the cylindrical outer casing and having a sight opening.

Fig. 5 is a projected plan of the glass cylinder having the illuminable lettering.

Fig. 6 is a perspective of a modified form of indicating mechanism.

The indicator mechanism 1 is mounted upon the front face of the radiator and the indicator mechanism 2 is mounted upon the rear end of the automobile. The indicator mechanisms 1 and 2 are substantially alike except that they are right and left.

The details of the indicator mechanism 1 are shown in Figs. 2, 3, 4 and 5. A stationary metal cap 3 has an annular retaining flange 4 extending one way from its edge and an attaching ear 5 extending the other way. A similar stationary cap 6 has an annular retaining flange 7 extending toward the flange 4, an attaching ear 8 extending in the other direction, and an arm 9 extending radially. The stationary cap 3 has a central opening 10 and the stationary cap 6 has a central opening 11.

The movable cap 12 has a pintle 13 fitting rotatably in the opening 10 and a nut 14 screw-seated upon the outer end of the pintle 13 to hold the cap rotatably in place, and the cap 12 has an annular retaining flange 15 extending in the opposite direction from the pintle 13. The movable cap 16 has an annular retaining flange 17 extending toward the flange 15 and a pintle having a

smooth portion 18 fitting rotatably in the opening 11 and a screw-threaded portion 19 extending beyond the cap 6.

The lamp socket 20 is secured against the inner face of the movable cap 16 and the lamp 21 is mounted in the socket 20. Electric wires 22 extend through a central opening 23 in the pintle and movable cap 16 to the lamp socket 20.

The glass cylinder 24 fits between the movable caps 12 and 16 within the retaining flanges 15 and 17 and bolts 25 are inserted through the cap 16 within the cylinder 24 and screw-threaded into the cap 12 to hold the caps 12 and 16 in position upon the ends 70 of the cylinder 24.

The cylinder 24 is preferably made of clear glass with its body painted or enameled white, and the lines of lettering 26, 27, 28 and 29 painted or enameled to be translucent 75 and tinted light red or pink, so that the letters will be clearly visible or readable in daylight and so that they will be illuminated by the lamp 21 to be visible and readable at night. If desired the glass may be 80 of the desired coloring for the lettering and then the body may be enameled or painted to leave the lettering translucent and the body opaque.

The metal cylinder 30 fits the inner faces 85 of the stationary caps 3 and 6 within the flanges 4 and 7 and the cylinder has a sight opening 31 adapted to expose one of the lines of lettering at a time; so that when the glass cylinder is rotated the words 90 "Stop", or "Left", or "Going", or "Right" may be exposed through the sight opening 31 as desired.

A spur pinion 32 is screwed upon the thread 19 and held in place by a pin 33. A swinging arm 34 is pivotally connected to the lower end of the rigid arm 9 by a shouldered bolt 35, and a segmental gear rack 36 is formed integral with the outer end of the movable arm 34 and meshes with the pinion 32, said rack being long enough to rotate the pinion a full three-quarters of a revolution. An ear 37 is formed integral with the arm 34 and gear rack 36.

In the indicator 1 the sight opening 31 will be in position to throw the light forwardly and in the indicator 2 the sight opening 31 will be in position to throw the light backwardly.

A clip 38 is mounted upon the steering 110

post casing 39, a lever 40 is pivotally mounted upon the clip 38, a connection 41 leads from the upper end of the lever 40 to the ear 37 on the indicating mechanism 1, and 5 a similar connection 42 leads from the lower end of the lever 40 to the ear 37 on the indicating mechanism 2. An arm 43 extends from the center of the lever 40 at right angles, a bell crank lever 44 is pivotally mounted at the upper end of the steering post casing 39, and a connecting rod 45 connects the short end of the bell crank lever 44 to the arm 43. A four-point sector 46 is fixed upon the upper end of the steering post casing 39 in position to coöperate with the handle 47 extending from the bell crank lever 44. 10 Preferably the parts are arranged so that when the handle 47 is in its forward position, as in Fig. 1, the word "Stop" will show 15 from the indicator mechanisms 1 and 2, and when the handle 47 is moved to the second point the word "Left" will show and at the third point the word "Going" will show and at the fourth point the word "Right" will 20 show.

In Fig. 6 I have shown a modified form 25 of the indicating mechanism 1 which is especially intended for use upon the front end of the automobile. The rectangular plate 30 48 is lettered on one side "Left" and on the reverse side "Right", and pintles 49 and 50 extend from the ends of the plate and are mounted in bearings in the supporting brackets 51 and 52, and the supporting 35 brackets are adapted to be secured to the front end of the radiator. The gear 53 is fixed upon the end of one of the pintles and the gear rack 54 is pivoted to the bracket 52 and meshes with the gear 53, and the cord 41 40 may be connected to this gear rack.

The gear 32 and coöoperating parts or the gear 53 and the coöperating parts will preferably be inclosed in a casing to improve the

appearance and to protect the parts from injury.

Thus I have made a direction indicator which will show simultaneously at both ends of the automobile, which may be easily read in daylight or dark, and which may be easily operated from the driver's seat.

Various changes may be made in the details of construction without departing from the spirit of my invention as claimed.

I claim:

1. An indicating mechanism comprising 55 two stationary caps, a stationary cylinder mounted between the caps and having a sight opening, ears for attaching the caps to a support, a rigid arm extending from one cap, rotatable caps mounted inside of the 60 stationary caps and having pintles extending through the stationary caps, a glass cylinder mounted between the rotatable caps and having illuminable lines of lettering adapted to appear through the sight opening, a spur pinion upon one of the pintles, a movable arm pivotally connected to the rigid arm and having a rack engaging the spur pinion, and means for operating the movable arm from a hand-lever mounted on the 65 steering post.

2. An indicating mechanism comprising a stationary cylinder having a sight opening, rotatable caps mounted inside of the 70 ends of the cylinder and having pintles extending through the ends of the cylinder, a glass cylinder mounted between the rotatable caps and connecting the caps together, a spur pinion upon one pintle outside of the 75 stationary cylinder, an arm rigid with the stationary cylinder, and a second arm pivotally mounted upon the first arm and having a rack engaging the spur pinion.

In testimony whereof I have signed my name to this specification.

ALTON W. INGALLS.
